UNITED STATES PATENT OFFICE.

FERDINAND SCHAUB, OF JERSEY CITY, NEW JERSEY; HENRIETTA W. SCHAUB EX-
ECUTRIX OF SAID FERDINAND SCHAUB, DECEASED.

INSULATOR.

Application filed May 21, 1920. Serial No. 383,109.

To all whom it may concern:

Be it known that I, FERDINAND SCHAUB, a citizen of the United States, residing at Jersey City, in the county of Hudson and State of New Jersey, have invented new and useful Improvements in Insulators, of which the following is a specification.

The present invention relates to insulators such as are customarily employed for supporting conductors for electric current.

Heretofore insulators of the class referred to have usually been in the form of cleats or knobs, the conductors being held in seats provided in the cleats or knobs which usually comprise two sections, a base section and a cap or head section. Taking the knob, for instance, the base and cap sections were centrally apertured, each embodying a complementary groove which, when the two sections were mounted upon a support, by means of a nail, screw or the like passing through the central apertures therein, registered to form the conductor seat. The pressure for holding the conductor within the seat was obtained through the medium of the nail, screw or the like, by means of which the sections were held together and on the support. These two-part insulators have been found to be objectionable, owing to the time consumed in assembly, since it is obvious that the centrally located apertures must be aligned which is also true of the half seat grooves. Furthermore, a considerable amount of breakage occurs in the handling and installation of these insulators by reason of lack of skill or carelessness on the part of those making the installations. To overcome the disadvantages of the type of insulators described, it has been proposed to provide some means whereby the insulator sections could be assembled prior to installation. One method followed, for instance, consisted in seating the nail, screw or other securing means in the registering central apertures of the base and cap sections and forcing over the shank or extending portion of the nail or screw a sleeve which was formed to frictionally engage the nail or screw shank at some point thereon to enable the sections to be separated a sufficient distance to seat the conductor therebetween. The diameter of this sleeve was greater than that of the central aperture

in the base section, so that after the location of the sleeve upon the shank of the nail or screw, the components of the insulator could not be accidentally disassembled. Other expedients along the same lines embody the use of a flat washer in frictional engagement with the shank of the nail or screw and movable within the recess of the base section or a flat washer or disk in contact with the flat washer or disk on the nail or screw shank in contact with the lower edge of the base section, in each instance the nail or screw being capable of longitudinal movement through the securing medium so that it could be embedded in the supporting surface.

It has been found that the means for maintaining the insulator sections in assembled relation do not wholly overcome the objections to the form of insulator which it is necessary to assemble on the work. The addition of the securing medium adds to the expense of production, not only in material but in labor, and in installation the complementary grooves of the sections forming the conductor seats must be brought into alignment before the nail or other mounting device is driven home or embedded in the supporting surface. If the portions of the conductor seats are not aligned, obviously breakage of one or the other, or both, of the insulator sections will result.

The present invention is designed to overcome many of the defects and disadvantages of the types of insulators heretofore referred to in a simple and economical manner, all of the advantages of an assembled insulator as now constructed being retained, the advantages being multiplied by features of construction which could not be obtained in the prior art.

The primary object of my invention is to provide an insulator made in one piece or in sections united to form an integral structure which will have portions corresponding generally to the base and cap sections of the usual form of insulator, the components of the conductor seat being at all times in registering relation.

A further object of my invention is to provide an insulator, as aforesaid, wherein the portions corresponding to the base and cap of the usual insulator are spaced apart

substantially throughout their entire opposing surfaces, whereby the conductor may be instantly located in its seat without manipulation of the insulator parts to bring 5 the half-seat-grooves in alignment.

Another object of my invention is to provide a means for mounting the insulator upon a suitable supporting surface, which means may comprise a nail or screw passing 10 through the insulator and provided with a surface or element to render its accidental removal from the insulator impossible, so that the insulator and the attaching means, such as a screw or nail or the like, may be 15 sold or distributed as a complete unit ready for installation.

My invention further contemplates an insulator possessing the aforesaid advantages and characteristics, in which the functioning of the portions within which the grooves forming the conductor seats are located is accomplished in the usual manner, that is, by the pressure imposed upon the portion corresponding to the cap of a two part insulator by embedding or locating the attaching means in the supporting surface.

Other objects and advantages of my invention will become manifest as the description proceeds, and I would have it understood that I reserve unto myself the full range of equivalents, both in structure and uses, to which I may be entitled under my invention in its broadest aspect.

I shall now proceed to describe my invention with reference to certain preferred embodiments which I have elected to show in the accompanying drawings, and will then point out with more particularity the essential elements of novelty residing therein in 40 the appended claims.

In the drawings,

Figure 1 is a view in elevation of an insulator made in accordance with my invention looking in a direction longitudinally 45 of the conductor seat;

Fig. 2 is a view similar to Fig. 1, looking transversely of the conductor seat;

Fig. 3 is a sectional view of the structure shown in Figs. 1 and 2, illustrating the position of the insulator components when 50 in functioning relation to a conductor;

Fig. 4 and 5 are respectively sectional views of fragments of the insulator shown in Fig. 3, illustrating means whereby the 55 attaching devices are secured against accidental removal from the insulator;

Fig. 6 is a sectional elevation, looking in a direction longitudinally of the conductor seats, of a so-called insulator of the 60 wedge-type made in accordance with my invention; and

Fig. 7 is a view similar to Fig. 6 illustrating the manner in which the conductor 65 is held in position when the insulator is in functioning condition.

Referring now to the drawings in detail, in which like characters of reference are employed to designate similar parts throughout the several views, 7 indicates the base or supporting portion of the insulator which is recessed at 8 and formed with the usual central aperture 9 and semi-annular groove 10 forming one-half of the conductor seat. Superposed upon the base portion 7 and connected thereto by the wall 11 70 is the top or cap portion of the insulator designated by the reference character 12. The said cap or top portion 12 is formed with the usual semi-annular groove 13 adapted to register with the groove 10 in 75 the base member 7 to form the conductor seat.

It will be observed that the portions 7 and 12 of my improved insulator correspond to the base and cap sections of the 80 commonly known two-piece insulator of the knob type, the function of the members 7 and 12 being the same as in the latter.

In the production of an insulator made in accordance with my invention, the base and cap members 7 and 12, respectively, are united or joined together by the aforesaid wall 11 in a manner whereby the cap 12 will be spaced from the upper surface of the base portion 7, and will preferably lie 90 in a plane inclined upwardly from the point or surface of joinder with the said base portion. (See Figs. 1 and 2). This allows a space between the opposed surfaces 7^a and 12^a of the members 7 and 12, respectively, large enough to permit of readily locating a conductor in the lower seat section 10 for engagement by the upper seat section 13 of the cap member 12, as herein-after explained.

The insulator, consisting of the portions 7 and 12, may be made or molded as an integral structure, or these members may be formed separately and joined so as to provide the wall 11 for supporting the cap portion 12 from the base portion 7, as described, the upper conductor seat section 13 being at all times in registering position with the lower conductor seat section 10.

In carrying the objects of my invention 115 into effect, I have found it preferable to form the insulator of porcelain or other frangible material, though it is obvious that it may be made of any suitable, yieldable or non-yieldable insulating material which 120 will permit of the movement of the cap portion 12 toward the base portion 7 to clamp the conductor therebetween in the manner hereinafter described.

Assuming that the insulator is formed of 125 porcelain or glass, the attaching device which may be a nail, as shown at 14, or a screw, as indicated at 15', having a washer 15 of a preferably yieldable material positioned in contact with the head thereon, is located in 130

the central apertures 9 and 16 of the base and cap portions 7 and 12, respectively. To prevent the accidental removal of the attaching means, a suitable stop wider than the 5 diameter of the apertures 9 and 16 in the base and cap portions 7 and 12, respectively, is located upon or associated with the shank of the said means. This stop may take the 10 form of the wings 17 formed by flattening out the material of the shank of the nail, as shown in Fig. 3, or may be a washer, as indicated at 18, which is held in frictional engagement with the shank of the nail or screw. The insulator, including the attaching 15 device secured against accidental removal therefrom, is preferably distributed as a single unit ready for installation.

To install and function the insulator, the base portion 7 is placed upon the supporting 20 surface, and the attaching device engaged therewith in the customary manner to permit of the location of the conductor between the base and cap portions for engagement by the semi-annular grooves 10 and 13, respectively. The inclination of the cap portion 25 relatively to the base portion of the insulator permits the user to locate a conductor of the greatest diameter with which a specific size of insulator is designed to function with the utmost facility.

Following the location of the conductor, the attaching device is driven home in the supporting surface, the pressure exerted upon the cap portion 12 through the medium 30 of the washer 15 by the movement of the attaching device relative to the cap, resulting in the fracture or breakage of the wall of joinder 11. This permits the cap to engage and cooperate with the base portion to 35 clamp the conductor therebetween in the customary manner, as shown in Fig. 3, the conductor being indicated by the reference numeral 19.

From the foregoing, it will be observed 40 that where a frangible material is used, the fracture or breakage of the wall of joinder 11 separates the cap portion of the insulator from the base portion thereof, so that all of the advantages of the well known two-piece 45 knob insulator are retained. Furthermore, positive registry of the semi-annular grooves in the base and cap portions which form the conductor seat, with the conductor, is as- 50 sured, so that the insulator and the conductor may be installed in a minimum amount of time.

If the insulator is made of other than a 55 frangible material, obviously the wall 11 will buckle or yield to an extent under the pressure exerted thereon by the driving home of the attaching means to permit the cap 12 to approach the base portion 7 and effect the clamping of the conductor therebetween with the same force and effect as would be obtained by a two-piece knob or a knob of

frangible material made in accordance with my invention. A further advantage of making the insulator of a yieldable material resides in the fact that the cap portion 12 will be capable of yielding under pressure in a 70 direction away from the base portion, if, under some conditions of use, it is found necessary to use a particular size of knob for supporting a conductor of a larger diameter than that with which such knob is customarily employed. 75

In Figs. 6 and 7 of the drawings, I have shown my invention applied to a knob or insulator of the so-called "wedge" type, such as disclosed in Letters Patent No. 919,386, 80 issued to me April 27, 1909, the functioning of the elements of this structure being similar to that described with reference to Figs. 1 to 5, inclusive, with the exception of the surfaces forming the conductor seat which 85 cooperate as described in my said Letters Patent.

While I have described my invention with reference to the preferred embodiment illustrated in the drawings, it is obvious that various changes in details of structure may be made without departing from the spirit and scope of my invention, which is broadly directed to an insulator having a base portion and a cap portion joined or connected to 90 permit of the bodily movement of the cap portion toward the base portion as and for the 95 purposes described.

I claim:

1. An insulator formed of a frangible material having spaced portions corresponding to the base and cap portions of a two-piece insulator integrally connected by a wall, said wall being adapted to be broken 100 under pressure to separate the portions connected thereby and provide a two-piece insulator. 105

2. An insulator formed of a frangible material having portions spaced apart to receive a conductor and connected by a wall, said wall being adapted to be broken under pressure to permit of the separation of said portions for clamping the conductor therebetween. 110

3. A one-piece insulator having a conductor receiving groove and a wall connecting the portions above and below the groove, said wall being adapted to be broken when the insulator is mounted to form a two-piece 115 insulator. 120

4. An insulator comprising a base portion and a cap portion connected thereto and spaced therefrom, the connection between said base portion and said cap portion being capable of being broken upon the application of pressure to said cap portion, to separate the cap portion from the base portion. 125

5. A one-piece insulator having a conduc- 130
